UNITED STATES PATENT OFFICE.

JOHN EDWARD SMITH, OF BRAZILTON, KANSAS.

TONGUE-SUPPORT.

SPECIFICATION forming part of Letters Patent No. 439,202, dated October 28, 1890.

Application filed July 22, 1890. Serial No. 359,531. (No model.)

To all whom it may concern:

Be it known that I, JOHN EDWARD SMITH, a citizen of the United States, residing at Brazilton, in the county of Crawford and State of Kansas, have invented a new and useful Tongue-Support, of which the following is a specification.

The invention relates to improvements in tongue-supports.

10 The object of the present invention is to simplify and improve the construction of tongue-supports and attach them to the body of a vehicle and prevent them interfering with the run of the same.

15 The invention consists in the construction and novel combination and arrangement of parts, hereinafter fully described, illustrated in the accompanying drawings, and pointed out in the claim hereto appended.

20 In the drawings, Figure 1 is a perspective view showing the tongue-support constructed in accordance with this invention attached to a vehicle and supporting the tongue of the same. Fig. 2 is a detail sectional view of the

25 spring, the diverging rods being illustrated in elevation. Fig. 3 is a detail sectional view of the spring. Fig. 4 is a detail perspective view of the clamp.

Referring to the accompanying drawings, 1
30 designates the dash-board of a vehicle pro-
vided on its front face with vertical strips 2,
having perforations 3 near their upper end, in
which is arranged a horizontal rod 4, extend-
ing across the front of the body of the vehicle
35 and extending beyond the vertical strip 2,
and providing means for attaching divergent
rods 5, formed integral with each other and
provided at their ends with hooks 6, adapted
to engage the extended ends of the horizontal
40 rod 4. The divergent rods 5 are constructed
of a single piece, which is bent midway its
length to provide an eye 7 to receive a hook
8, that connects the divergent rods with a
spring 9, and the ends of the divergent rods 5
45 are slightly curved or bent to clear the verti-
cal strips 2. The spring 9 is spiral and has
its ends secured to the ends of oppositely-dis-
posed loop rods or staples 10, arranged within
and forming loops at the end of the spring,
50 one of which loops is attached to the hook 8,
and the other is provided with a chain 11,
forming convenient means for connecting the

spring to a clamp 12 of the tongue 13. The
ends of the loop rods or staples 10 are pro-
vided with eyes formed by bending the end 55
around the outer coil of the spring, and when
the loop rods or staples are pulled upon their
ends are drawn toward each other, thereby
compressing the spring, which forms a cush-
ion. 60

The clamp 12 consists of two sections 14,
having their upper ends secured together by
a rivet 15, which also secures a hook 16 to the
clamp to engage the chain 11, and the lower
ends of the sections are perforated and 65
adapted to receive a bolt or rivet 17, arranged
beneath the tongue and securing the clamp
thereto.

From the foregoing it will be readily seen
that the tongue-support is simple and com- 70
paratively inexpensive in construction, and is
adapted to be readily attached to the body of
the vehicle and tongue, and will not interfere
with the run of the vehicle.

Having described my invention, what I 75
claim is—

The combination, with a vehicle having its
body provided with the vertical strips 2, and
the horizontal rod passing through perfora- 80
tions of the strips and having its ends ex-
tended beyond the latter, of the divergent
rods constructed of a single piece doubled to
form a loop 7, and having its ends slightly
curved and provided with hooks engaging the
extended ends of the horizontal rod, the spiral 85
springs, and the oppositely-disposed loop rods
or staples arranged within the spring and
having their ends provided with eyes and se-
cured to the outer coil of the spring, said
loop rods or staples being extended beyond 90
the ends of the spring to provide loops, the
upper one being connected to the eye of the
divergent rods by a hook and the lower one
being provided with a chain adapted to be
attached to the tongue of the vehicle by a 95
clamp, substantially as described.

In testimony that I claim the foregoing as
my own I have hereto affixed my signature in
presence of two witnesses.

JOHN EDWARD SMITH.
